UNITED STATES PATENT OFFICE

2,601,046

GARMENT CONSTRUCTION

Herman M. McDonald, Evanston, Ill., assignor to
Dorothy L. McDonald, Evanston, Ill.

Application February 15, 1951, Serial No. 211,153

4 Claims. (Cl. 2—90)

1

This invention relates to garments such as slipover type sweaters, T-shirts, and the like, and is directed more particularly to the collar construction of such garments.

It has been found with such garments, particularly T-shirts that, after repeated washing, the collars thereof become permanently stretched out of shape thereby impairing the appearance thereof. As a further consequence of the collar becoming deformed, the garment frequently will not fit properly and thus becomes uncomfortable to wear.

Thus it is one of the objects of this invention to provide a garment having a collar which will retain its proper shape and conform to the neck of the wearer even after repeated washing and wearing thereof.

It is a further object of this invention to provide a collar construction which has a neat and attractive appearance and will not cause unsightly bulges to occur when worn beneath another garment.

It is a further object of this invention to provide a collar construction which is strong and durable and able to withstand excessive wear.

Further and additional objects will appear from the description, accompanying drawings, and appended claims.

In accordance with one embodiment of this invention a garment is provided comprising a body member made of yieldable fabric having a neck-conforming edge. Embracing the edge and extending therefrom a predetermined distance on opposite sides of the body member is a reinforcing piece made of like fabric. The piece is stitched to the body member at one point adjacent the neck-conforming edge and at a second point a predetermined distance from said edge. Partially embracing the piece is a fabric reinforcing element which is stitched to the piece and the body member at the first mentioned point.

For a more complete understanding of this invention reference should be made to the drawings, wherein

Fig. 1 is a fragmentary perspective view of the garment shown being worn;

Fig. 2 is a fragmentary perspective view of the garment showing sections of the collar turned back to expose the various portions thereof; and

Fig. 3 is an enlarged fragmentary sectional view of the garment taken along line 3—3 of Fig. 2.

Referring now to the drawings and more particularly to Fig. 1, a garment 10, which in this instance is a T-shirt, is shown having a collar 11

thereof which is adapted to conform to the neck 12 of the wearer 13. The garment 10 is made of a yieldable fabric, such as a knitted cotton material, and comprises a body or shirt portion 14 having the upper edge 15 thereof rounded and shaped to conform substantially to the neck of the wearer 13. Mounted on body member 14 and embracing edge 15 is a reinforcing piece 16 which engages the opposite sides of the garment 14, as shown in Fig. 3. Piece 16 is made of the same material as body member 14 and has the side portions 16a and 16b thereof extending a predetermined distance from the edge 15 of member 14. A portion 17 of the exposed side 16a is turned back under to form a hem. The turned-back portion 17 is spaced a predetermined distance from edge 15 and is secured to member 14 by a double row of stitching 18. The turned-back portion 17 of piece 16, co-operates with body member 14 to provide four-ply or quadruple thickness of material at the rows of stitching 18. The portion of garment 14 between stitching 18 and edge 15 is of three-ply or triple thickness construction.

25 Mounted on piece 16 is a second reinforcing element 20 which is made of the same material as body member 14 and piece 16. Element 20 is adapted to embrace the portion of piece 16 which is adjacent the edge 15 of member 14. The exposed side 20a of element 20 is provided with a portion 21 which is turned back under to form a hem which is secured by a double row of stitching 22 to piece 16 and edge 15 of member 14. Hem portion 21 co-operates with piece 16 and edge 15 to provide six-ply or sextuple thickness of material at the stitching 22. The effect of the six-ply and four-ply construction at stitchings 22 and 18, respectively, is to retain the proper shape of the collar.

30 The stitches 18 and 22 at the inside of the garment are zigzag or herringbone in form, as shown at 18a and 22a, respectively, and firmly confine and secure the raw edges of the inside portions 16b and 20b of the piece 16 and element 20, see Figs. 2 and 3.

35 The resiliency of the fabric allows the stitched portions of the collar to yield a sufficient amount so as to enable the wearer to readily slip the garment on or off. However, the combined resiliency of the sextuple or quadruple thickness of material causes the collar to resume its proper shape once the head of the wearer 13 has passed therethrough. The reinforcing piece 16 and the element 20 also give added strength and durability to the garment 10 and materially increase

the wearing qualities thereof. Furthermore, the reinforcing piece 16 and element 20 preserve the neat and attractive appearance of the garment 10 and also co-operate with each other to make a pleasing collar design.

While Fig. 3 gives the impression that hem portions 17 and 21 tend to give a bulging appearance to the collar it should be understood that this is due entirely to the enlargement of the view and that in reality the thickness of the fabric is such that the protrusion of these hem portions would be negligible. Thus the garment may be readily worn as an under-garment without causing any noticeable bulges.

While the figures illustrate a T-shirt, it is to be understood, of course, that such collar construction may be readily adapted for use in other garments such as sweaters and the like.

It will be seen that a garment has been provided having a collar which will retain its proper shape and thus the neat and attractive appearance of the garment, even after excessive washing, is preserved. Furthermore, a collar construction is provided which will improve the wearing qualities of the garment.

While a particular embodiment of this invention has been shown, it will be understood, of course, that the invention is not to be limited thereto since many modifications may be made, and it is contemplated, therefore, by the appended claims to cover any such modifications as fall within the true spirit and scope of the invention.

I claim:

1. A garment made of yieldable fabric comprising a fabric body member having a neck-conforming edge, a first fabric-reinforcing piece embracing said edge and secured to said member along a first line adjacent said edge and along a second line spaced from said edge, and a second fabric reinforcing piece embracing that portion of said first reinforcing piece adjacent said edge and secured to said first piece and said body member along said first line.

2. A garment made of yieldable fabric comprising a fabric body member having a neck-conforming edge, a fabric edge-embracing first piece attached to said member along a first line adjacent said edge and along a second line spaced from said edge thereby effecting at least triple thickness of fabric between said lines of attachment, and a second fabric piece partially embracing said first piece and attached to said

first piece and said body member adjacent said first line thereby effecting at least quintuple thickness of fabric adjacent the edge of said body member.

3. A garment made of yieldable fabric comprising a fabric body member having a neck-conforming edge, a fabric edge-embracing first piece having sides depending downwardly on opposite sides of said body member for substantially the same distance and having a hem portion disposed on a lower edge of one side thereof, said hem portion and the lower edge of the opposite side of said first piece being secured to said body member along a line spaced from said edge to provide at least quadruple thickness of fabric along said line, and a second fabric piece partially embracing said first piece and having a second hem portion disposed on an edge of one side thereof adjacent said neck-conforming edge, said second hem portion and the opposite side of said second piece being secured to said first piece and said body member along another line adjacent said edge to provide at least sextuple thickness of fabric adjacent said edge.
4. A garment having a neck opening and comprising a knitted fabric body member having a neck-conforming edge, a knitted fabric reinforcing first piece embracing said edge and secured to said member along a first line adjacent said edge and along another line spaced from said edge, and a knitted second piece embracing the portion of said first piece adjacent said edge and secured to said first piece and said member along said first line, the upper edge of said second piece being spaced a substantial distance above the upper edge of said first piece thereby providing only a double layer of fabric adapted to embrace the neck of the wearer.
